CLAIM

The ornamental design for a kettle body, as shown and described.

DESCRIPTION

FIG. 1 is a front view of a kettle body, showing our new design;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

1 Claim, 7 Drawing Sheets
